CLAIM

The ornamental design for a goods display stand, as shown and described.

DESCRIPTION

FIG. 1 is a front view of a goods display stand showing my new design;

FIG. 2 is a top view thereof;

FIG. 3 is a rear view thereof;

FIG. 4 is a bottom view thereof;

FIG. 5 is a right view thereof, the left view thereof being a right-and-left-reversed image;

FIG. 6 is an end view taken through line 6-6 of FIG. 1; and,

FIG. 7 is a front perspective view thereof.
